04-124

AU 291

EX

OR 0 28,409

DESIGN.

T. W. FOSTER.
COVER FOR BRUSH BACKS.

No. 28,409.

Patented Mar. 29, 1898.

Fig. 1.

Fig. 2.

Witnesses.

Chas. H. Luther Jr
B. M. Simms

Inventor.

Theodore W. Foster
J. Joseph A. Miller & Co
Atkrs.

UNITED STATES PATENT OFFICE.

THEODORE W. FOSTER, OF PROVIDENCE, RHODE ISLAND.

DESIGN FOR A COVER FOR BRUSH-BACKS.

SPECIFICATION forming part of Design No. 28,409, dated March 29, 1898.

Application filed October 4, 1897. Serial No. 654,087. Term of patent 3½ years.

o all whom it may concern:

Be it known that I, THEODORE W. FOSTER, citizen of the United States, residing at Providence, in the county of Providence and state of Rhode Island, have invented and produced a new and original Design for the Covers of the Backs of Brushes and Similar Articles, of which the following is a specification, reference being had to the accompanying drawings, forming part thereof.

Figure 1 is a plan view of an oval brush-back cover showing my new design. Fig. 2 is a sectional view of the cover.

The leading and material feature of my design consists in the scalloped outline of the plain surface of the cover and the floral wreath extending parallel with the outer edge of the cover within the scalloped outline.

In the drawings, 3 indicates the outline of the cover 3'. This outline may be of oval form, as is shown in Fig. 1. At intervals along the margin of the cover the inwardly-curved lines 4 form triangular recesses 5, giving to the plain surface of the cover a scalloped outline. The triangular recesses 5 are ornamented with a floral design resembling a forget-me-not. The floral wreath is formed alternately of the floral group 6, consisting of the rose 7 in the center of the rose-leaves 8 8, from which extend a number of stems terminating each in a calyx 9, resembling a heliotrope, and the floral group 10, in which the conventional form of the flower known as "forget-me-not" forms the center, from which floral stems and leaves radiate, the stems terminating in calyxes resembling heliotropes, the whole forming an open floral wreath the general form of which corresponds to the form of the cover.

Having thus described my newly-produced design, what I claim as new, and desire to secure by Letters Patent, is—

The design for the cover of the backs of brushes and similar articles herein shown and described.

THEODORE W. FOSTER.

Witnesses:

JOSEPH A. MILLER, Jr.,
B. M. SIMMS.